2

1 The subject-matter of the invention is an improved transformer for use in machine and apparatus utilizing the transformation of circular motion (continuous, uniform, variable or alternating) into intermittent motion. Although said improved transformer has been designed mainly for use in apparatus for taking, projecting and printing motion pictures, it is not intended to be restricted to such use, for it may also be applied, by way of example, to straw binding machines, sacking machines, packing machines, machines for boxing powdered or solid products, oil or vapor distributors, certain machine tools such as automatic lathes and their appliances such as automatic dividing heads for milling or other machines, calculating machines, electrical contactors with periodically varying resistance, machines for printing papers or fabrics, obliterating machines, etc.

Said improved transformer permits of changing an initial circular uniform, variable or alternating motion into a resulting intermittent circular motion, which is always of the same sense as that of the initial motion; it is further of constant amplitude in the space and of constant period as to its duration, as long as the initial motion remains continual; finally it comprises a fixed division into complete fraction of a revolution, for example a third, a quarter, etc.; in other terms, the amplitude is $2\pi R/n$, n being a full number superior to 2, whatever the initial motion may be, the stopping after each travel through length $2\pi R/n$ being of constant duration when the initial motion is uniform.

On the other hand, according to the invention, said intermittent circular motion may in turn communicate a rectilinear or curvilinear intermittent motion to a member sliding in a curvilinear or rectilinear passage and which may be constituted either by a rigid part such as a rack, or by a flexible band, endless or of great length, such for example as a motion picture film, this result being obtained by suitably setting said member in contact with a cylindrical part endowed with an intermittent circular motion above stated.

Many various arrangements, mechanical, hydraulic, pneumatic, electrical, have already been proposed to solve the problem of transformation above referred to. Nonmechanical arrangements involve the drawback that the resulting motion is inaccurate and undesirably changeable, so that they are little used. As to mechanical arrangements, most of these in use, particularly in the motion picture industry, are

of Maltese cross and claw types each of which involves serious drawbacks that can be remedied in part only and by way of objectionable constructions.

5 Transforming apparatus according to the present invention permits of avoiding the drawbacks inherent to said Maltese cross and claw transformers and, on the other hand, has a number of advantages that will be set forth hereinafter. **10** This apparatus comprises substantially two cams mounted on parallel axles or preferably on one and the same axle, and caused to rotate continually. One of these cams is adapted to impart, through the medium of a pivoting crank or lever terminated by a pin, a rotation through $2\pi/n$ radians to a disc provided with n holes or peripheral notches (n being greater than 2) generally spaced regularly; the axis of this disc may be parallel to the axis about which said lever pivots and to that of the pin, or it may preferably coincide with the latter without being constantly in fast relation thereto; this disc axis is further preferably parallel to the axes of said two cams. As to the other cam, this is adapted **15** to impart to said lever a motion of translation along its axis for the purpose of either setting the pin thereof into engagement with the disc, or causing the lever to stop the rotation of the disc when this has rotated through $2\pi/n$. This second cam further causes, through the medium of a slider or translator, the displacement of a member that comes to stop the disc after this has rotated through $2\pi/n$, and after having preferably imparted to the disc a slight additional **20** rotation to cause the same to stop in a strictly defined position.

Besides the principal arrangement just stated, the invention comprises the following additional appliances that may be used simultaneously:

25 1. At the end of the shaft supporting the disc is arranged a cylindrical member that may be constituted by a sprocket drum and serves to drive a rigid or flexible member that may be of great length, such as a motion picture film. **30** 2. When the resisting member to which the intermittent motion should be imparted has a velocity of displacement such that, consequent upon the effects of inertia resulting from necessary plays and from wear and tear of the effects of elasticity of materials employed and the effects of resistances to drive which may slightly vary for the n stop-positions of the disc, this member does not travel exactly the same distance at each intermittence and, consequently, **35** does not stop in exactly predetermined positions,

the disc is given, at the time of its stopping, a motion complementary of that imparted thereto by the pivoting lever. This complementary motion, of feeble amplitude, may, in the case of a motion picture apparatus, be in the order of from $\frac{1}{100}$ to $\frac{1}{5}$ millimeter and preferably effected in the same sense as that imparted to the disc by pivoting lever. To this end, the axis of the pivoting lever pin is made parallel to that of the disc stopping spigot and both the pin and spigot are cone-shaped, the disc stopping positions being so arranged that, at the end of the phase of rotation effected by pivoting lever, the disc is given, owing the cone-shaped spigot, an additional motion of feeble amplitude and at speed sufficiently slow to prevent the effects of inertia from being felt.

3. The ensemble of apparatus is confined in a casing, except for the sprocket drum or the like, so designed that the two cams may operate immersed in oil, without oil projections.

In order that the invention may be more clearly understood, the same will now be described with reference to the accompanying more or less diagrammatic drawings which show by way of example some embodiments of the invention applied more particularly to a motion picture apparatus, and in which:

Fig. 1 is a sectional elevational view showing the various parts of apparatus according to the present invention, the axis AA being disposed in the plane of the paper, while the axes BB and CC, which coincide, as well as the axes DD and EE are situated behind the plane of the paper;

Fig. 2 is a view partly similar to Fig. 1, showing a modification of the parts disposed in Fig. 1 on the axes BB, CC and DD, these parts here being disposed on a single axis B₁B₁ coinciding with the axes C₁C₁ and D₁D₁, the axis A₁A₁ of the cam shaft being situated ahead of the plane of the paper;

Fig. 3 is a face view of a first form of disc to which the intermittent motion is communicated;

Fig. 4 is a face view of a second form of disc;

Fig. 5 is a face view of a third form of disc;

Fig. 6 is a face view showing a modified construction of both the disc and the disc stopping device;

Fig. 7 shows a cam controlling the disc stopping mechanism;

Fig. 8 shows a cam controlling the disc stopping mechanism;

Fig. 9 is a sectional view taken through the line XX of Fig. 1;

Figs. 10 to 14, inclusive, are enlarged sectional views showing in five successive positions the disc driving pin and the disc stopping spigot.

In these drawings similar characters of reference indicate like parts throughout the several views.

In the embodiment shown in Fig. 1 the ensemble of apparatus is confined in a casing 1 closed by a cheek plate 2 from which extends outwardly the driving shaft 3 actuated by hand or by a motor through pulley 4. Through the medium of helical gears 5 and 5' (Fig. 9) the motion of this shaft is transmitted to members (not shown, because not forming part of the present invention), such for example as the shutter and driving toothed drums intended for continual rotation.

Keyed onto the shaft 3 are two cams 6 and 7, which may be constituted by two distinct parts as shown in Fig. 1, or by a single block as shown

in Fig. 2. These cams, which may be of any suitable type, are, in the example shown, grooved cams, the cam 6 having a lateral groove 8 whose generating lines are parallel to the axis AA, while the cam 7 has a peripheral groove 9 whose generating lines are perpendicular to this axis AA.

Penetrating into the groove 8 of cam 6 is a follower 11 carried by a pivoting lever 10 of axis BB parallel to the axis AA and forming a kind of crank pin. In the example shown, the axis about which this lever 10 is pivoting is materialized by shaft 22. The follower 11 is guided by the cam slope groove 8 being sufficiently deep for the purpose, the cam 6 imparting, through the follower 11, an oscillating motion the law of which may be selected at will, depending on the design of the slope of groove 8. In this way there may be obtained a periodical motion constituted by a series of motions uniformly accelerated or not accelerated and uniformly decelerated or not decelerated; the times of accelerated or decelerated motions, separated, if expedient, by phases of immobility, may be selected to be unequal or equal; in other terms the time of oscillation of the lever may be, or may not be, shorter in one sense than in the other, and the times of the phases of immobility may be selected to be unequal or equal.

On the other hand, the lever 10 is provided at its inner end with a pin 12 of axis parallel to AA, intended to control a disc 13, of axis CC, preferably parallel to AA, to which this pin would communicate a circular motion of variable sense which would have exactly the same characteristics of variation as those of the oscillating lever 10, if the pin 12 remained in engagement with the disc 13. This would happen if there were no intervention by the cam 7 in the conditions that will be indicated hereinafter. In the mode of execution shown, the axis CC is materialized by a hollow shaft 20 adapted to rotate in the bossage 21 of casing 1 and to receive the axle 22 of lever 10.

It should be noted, however, that though the coincidence of the axes BB and CC constitutes a particularly interesting feature of the invention, such coincidence is not absolutely necessary.

The disc 13 may—and must, when the axes BB and CC do not coincide—be made as shown in Fig. 3 and provided on its periphery with parallelly faced notches 14, 15, 16, 17, 18, 19, six in number in the example shown, but their number may be greater or smaller at will, the angle formed by two consecutive notches being constant. It is into these notches that the pin 12 of lever 10 penetrates (Figs. 1 and 9).

When the axes BB and CC coincide, the disc may be of type 13¹ shown in Fig. 4 and comprise, instead of notches, mere holes 14'—19', of appropriate equidistant formation and equidistant from the disc center.

In the mode of execution shown in Fig. 1, penetrating into the slope groove 9 of cam 7 is a follower 23 carried by the arm 24 of a member herein called "translator" having two arms 24, 25 interconnected by a web slidable along the shaft 30 of axis DD blocked in casing 1. The arm 25 of this translator is terminated by a part 26 which, by acting upon abutments 27, 28 provided on the shaft 22, communicates a motion of translation to the lever 10 and, consequently, to the pin 12 which is thus disengaged, at the required time, from the notches or holes of the disc 13, wherefore the latter is stopped. Means, not

shown, are provided for preventing rotation of the translator 24-25-29.

On the other hand, the said translator is connected with a spigot 32 whose axis EE is preferably parallel to AA and whose tail is adapted to slide with great accuracy in a bore 31 managed in the casing 1, the arrangement being such as to allow the translator to displace the pin 12 and spigot 32 in the same sense in such a way that, when the pin 12 moves out of the disc 13, the 10 spigot 32 penetrates into one of the notches or holes of the disc, whereby the latter is immobilized. In this case, the disc may have two series of equidistant holes (Fig. 5): one comprising the holes 14', 15', 16', 17', 18', 19' intended for receiving the pin 12, and the other comprising the holes 14², 15², 16², 17², 18², 19² arranged at lesser distance from the disc center and intended for receiving the spigot 32.

It is clear that, with these arrangements, when the lever 10 rotates in a certain sense, it drives the disc 13 and causes the same to rotate through angle $2\pi/n$, while when this lever rotates in the opposite sense, the disc remains immovable.

According to a preferred embodiment of the invention, the various parts hereinabove are arranged in such a way that, at the very time when the disc 13 is to stop or when the pin 12 disengages itself from the disc notches and holes, the axis of the spigot 32 is not exactly in the axial plane of one of the notches 14 to 19 (Fig. 3) or of one of the holes 14' to 19' (Fig. 4) or 14² to 19² (Fig. 5) in the disc 13, but is slightly offset or shifted, for example in the case of motion picture apparatus, through from $\frac{1}{100}$ to $\frac{1}{5}$ millimeter, with respect to that of the notches or holes which is almost in front of the spigot. This slight shifting is so arranged that, when the oscillating lever 10 has ceased to communicate its motion to the disc, the latter continues or recommences to move a little further in the same sense, but slowly, under the action of the spigot 32 which to this end has been provided with a cylindrical portion topped by a cone shaped portion as clearly shown in the several drawings, in such a way that the disc is set into its final and exact stop-position first by the largest diameter of said cone shaped portion and then by said cylindrical portion of same diameter. The final position of the disc will always be extremely accurate since it will be implemented by a stop-spigot that will hardly wear off and since the total amount of normal plays will be very small.

This additional impulsion or "push-pull" imparted to the disc is best illustrated in Figs. 10 to 14. Fig. 10 shows the disc in its position as the end of being driven by the pin 12 of lever 10; in Fig. 11 the pin 12 has begun to withdraw from the disc and is about to discontinue its contact with the disc; in Fig. 12 this contact has ceased, while the spigot 32 in its turn comes in contact with the disc and begins to impart to the latter the desired "push-pull"; Fig. 13 shows the disc in its stop-position just at the end of "push-pull"; the cylindrical portion of the spigot 32 begins to come in contact with the disc 13 which is shown in Fig. 14 in its ultimate locking position.

As will be seen in Fig. 1, the ensemble of apparatus is confined in the casing 1 from which 70 protrudes outwardly the end of the shaft 29 which supports the disc 13 and onto which is keyed a drum 36 that receives an intermittent circular motion. This drum may be toothed, its teeth or sprocket protrusions being shown at 37; 75

it will serve, in the case of a motion picture apparatus, for driving a film (not shown) which will be subjected to an intermittent rectilinear or curvilinear motion of translation.

5 In this case, as the sprocket holes might have plays with respect to the sprocket drum and as the film in point might slip thereon, the latter might keep on moving when the sprocket drum stops prior to the spigot 32 becoming effective, and it might be possible that the step-by-step displacement of the film in its passage be not always identical, thereby rendering inaccurate the projection of the cinematographic film. Now, owing to the aforesaid "push-pull" imparted to the disc 13 and, consequently, to the sprocket drum 36, the film will keep on moving, in the sense of its travel, slowly for a very short time, thereby permitting the film first to take up the slip due to its inertia and then to be displaced at each step identically.

Many changes may be effected in the particular apparatus hereinabove described and shown, without substantially departing from the scope of the invention. Thus, Fig. 2 shows, on one hand, a modified form of translator and, on the other hand, a modified form of disc and its blocking means, the last named form being further shown in Fig. 6.

30 As to the translator, the three axes B₁B₁, C₁C₁ and D₁D₁ are all coinciding, and the translator is adapted to slide within the shaft 29 supporting the disc 13. In the mode of construction shown the translator 29' is rigid with the shaft 22 of lever 10 and, consequently, oscillates together with it. To make this motion effective the follower 23¹ penetrating into the slope groove of the cam 7 is formed with a ball 24¹ forming ball joint with a corresponding hollow in the groove 9.

35 On the other hand, the disc 13³ (Figs. 2 and 6) is provided, besides the notches 14-19 of Fig. 3 or holes 14¹-19¹ of Fig. 4, with peripheral cutaways 35 similar to those generally carried by Maltese crosses. Cooperating with this disc is an auxiliary disc 33 whose axle A'A' is rigid with the cams 6 and 7 and which has a peripheral cutaway 34.

40 When one of the protruding portions of the disc 13³ is in the cutaway 34 (Figure 6), the pin 12 will have penetrated into one of the holes 14-19, wherefore the disc is set in rotation. When this disc is to be stopped, the translator 29' (Fig. 2) will have displaced the follower 11 to the right, as viewed in Fig. 2, whereby the pin 12 is disengaged while the full portion of disc 33 comes to bear against a cutaway 35 and immobilizes the disc 13³.

45 A further form of disc immobilizing mechanism would consist in utilizing in the conventional way a cam-controlled pivoting pawl mechanism.

50 It is to be noted, however, that neither the auxiliary disc-mechanism of Fig. 6 nor the pawl-mechanism permit of utilizing the aforesaid "push-pull" mechanism the advantage of which has been set forth hereinabove.

55 The following modifications may further be considered:

1. Instead of sliding contact, the followers 11 and 23 may be arranged for rolling contact with the slope grooves of cams 6 and 7, respectively, by means of rollers mounted on cylindrical axles.

2. The oscillating lever 10 may be replaced by a translator causing the pin 12 to describe a trajectory parallel to the plane of the paper of

Fig. 1, this pin in turn being endowed with a motion of translation along its axis in a bore made within the translator.

Apparatus designed according to the invention has, in addition to its ability of doing away with the drawbacks inherent to Maltese cross and claw systems, the following particular advantages: (a) great accuracy of desired division into $2\pi/n$ and its obtainment with the aid of cylindrical or conical holes, or battlements, easy to machine; (b) possibility to cause the resisting body to revolve intermittently in accordance with a law that may be established at will, and consequently: (c) smooth starting and stopping; (d) greatest possible rapidity of the intermittent rotation; (e) almost silent operation; (f) absence of important vibrations; (g) feeble inertia stresses; (h) use, for blocking the disc, preferably of a cylindrical spigot with cone-shaped end adapted to move slowly into, and out of, the disc and only when the latter is in its stop-position, so that practically it does not wear off; (i) easy construction and repairs; (j) low prime cost.

When incorporated into motion picture machines, said apparatus has the following additional advantages: (a) luminescence of both projector and camera is independent from the number of sprocket teeth meshing with the film employed; (b) use may be made of a sprocket drum with great number of teeth to diminish fatigue and wear of the film; (c) absolute liberty to choose best suitable law of intermittent displacement of the sprocket drum and, consequently, of the film which may be given for example a uniformly accelerated motion followed by a uniformly decelerated motion; (d) possibility to increase considerably the number of images projected within a given time; (e) possibility to obtain a better timing of step-by-step film-displacement than as with the Maltese cross, hence brighter projections on the screen; (f) as the sprocket drum may be driven intermittently with a constant acceleration, it is possible, with the maximum inertia forces being inferior to those obtained in Maltese cross mechanisms, to have sprocket drums of greater diameter, despite the increased moment of inertia resulting therefrom; (g) pressure on the film in its passage is greatly reduced, for it is not necessary to apply a strong pressure against the film to immobilize the same rapidly as in heretofore apparatus, such reduced pressure having for its effect to considerably decrease wear of the film and electrostatic charges occurring therein; (h) perfect fixity of the image projected, despite long service of the apparatus, owing to the fact that the film stopping means remain in excellent working state.

What is claimed is:

1. A mechanism for converting continuous rotary motion into intermittent motion of constant amplitude and period comprising a driving cam and a stopping cam both rotatable with constant angular velocity, a driven shaft mounted in parallel relationship with said cams, a disc on said driven shaft, a rotatable crank arm adapted to engage said disc for imparting rotation thereto, a follower on said crank arm in driven engagement with the driving cam, a stopping device adapted to engage said disc to stop the rotation of same, and means operatively connected to said stopping device and including a cam follower in driven engagement with the stopping cam for stopping rotation of said disc after a predetermined angular movement thereof.

2. A mechanism for converting continuous rotary motion into intermittent motion of constant amplitude and period for driving motion picture film comprising a driving cam and a stopping cam both rotatable with constant angular velocity, a driven shaft mounted in parallel relationship with said cams, a drive sprocket mounted on said driven shaft for cooperation with the motion picture film and imparting thereto the motion of said driven shaft, a disc on said driven shaft, a rotatable crank arm adapted to engage said disc for imparting rotation thereto, a follower on said crank arm in driven engagement with the driving cam, a stopping device adapted to engage said disc to stop the rotation of same, and means operatively connected to said stopping device and including a cam follower in driven engagement with the stopping cam for stopping rotation of said disc after a predetermined angular movement thereof.

3. A mechanism for converting continuous rotary motion into intermittent motion of constant amplitude and period comprising a driving cam and a stopping cam both rotatable with constant angular velocity, a driven shaft mounted in parallel relationship with said cams, a disc on said driven shaft, a rotatable crank arm adapted to engage said disc for imparting rotation thereto when rotating in one direction and disengagable from said disc when rotating in the opposite direction, a follower on said crank arm in driven engagement with the driving cam, a stopping device adapted to engage said disc to stop the rotation of same when the crank arm is rotating in the latter direction, and means operatively connected to said stopping device and including a cam follower in driven engagement with the stopping cam for stopping rotation of said disc after predetermined angular movement thereof.

4. A mechanism for converting continuous rotary motion into intermittent motion of constant amplitude and period comprising a driving cam and a stopping cam both rotatable with constant angular velocity, a driven shaft mounted in parallel relationship with said cams, a disc on said driven shaft, a rotatable crank arm slidably mounted with respect to said driven shaft and having a follower thereon in driven engagement with the driving cam and a locking pin thereon engageable with the disc, a stopping device adapted to engage said disc to stop the rotation of same, and means including a shiftable member movable in parallelism with said driven shaft and the axes of said cams and a cam follower carried thereby in driven engagement with the stopping cam and operatively connected to said crank arm and said stopping device for selectively moving either the locking pin or the stopping device into engagement with said disc.

5. A mechanism for converting continuous rotary motion into intermittent motion of constant amplitude and period comprising a driving cam and a stopping cam both rotatable with the same angular velocity, a driven shaft mounted in parallel relationship with said cams, a disc on said driven shaft having a plurality of radially positioned and arcuately spaced notches therein, a rotatable crank arm slidably mounted with respect to said driven shaft and having a follower thereon in driven engagement with the driving cam and a locking pin thereon engageable in the notches in the disc, a stopping device also adapted to engage in the notches on said

disc to stop the rotation of same, and means including a shiftable member movable in parallelism with said driven shaft and the axes of said cams and a cam follower carried thereby in driven engagement with the stopping arm and operatively connected to said crank arm and said stopping device for selectively moving either the locking pin or the stopping device into registering notches in said disc.

6. A mechanism for converting continuous rotary motion into intermittent motion of constant amplitude and period comprising a driving cam and a stopping cam both rotatable with the same angular velocity, a driven shaft mounted in parallel relationship with said cams, a disc on said driven shaft having a plurality of radially positioned and arcuately spaced holes therein, a rotatable crank arm slidably mounted with respect to said driven shaft and having a follower thereon in driven engagement with the driving cam and a locking pin thereon engageable in the holes in the disc, a stopping device also adapted to engage in the holes in said disc to stop the rotation of same, and means including a shiftable member movable in parallelism with said driven shaft and the axes of said cams and a cam follower carried thereby in driven engagement with the stopping cam and operatively connected to said crank arm and said stopping device for selectively moving either the locking pin or the stopping device into registering holes in said disc.

7. A mechanism for converting continuous rotary motion into intermittent motion of constant amplitude and period comprising a driving cam and a stopping cam both rotatable with the same angular velocity, a driven shaft mounted in parallel relationship with said cams, a disc on said driven shaft having a first series of holes therein of uniform arcuate spacing and a second series of holes therein of uniform arcuate spacing but of different radial spacing, a rotatable crank arm slidably mounted with respect to said driven shaft and having a follower thereon in driven engagement with the driving cam and a locking pin thereon engageable in any one of the first series of holes in said disc, a stopping device adapted to engage in any one of the second series of holes in said disc to stop the rotation of same, and means including a shiftable member movable in parallelism with said driven shaft and the axes of said cams and a cam follower carried thereby in driven engagement with the stopping cam and operatively connected to said crank arm and said stopping device for selectively moving either the locking pin or the stopping device into the respective registering holes in said disc.

8. A mechanism for converting continuous rotary motion into intermittent motion of constant amplitude and period comprising a driving cam and a stopping cam both rotatable with the same angular velocity, a driven shaft mounted in parallel relationship with said cams, a disc on said driven shaft having a plurality of radially positioned and arcuately spaced holes therein, a rotatable crank arm slidably mounted with respect to said driven shaft and having a follower thereon in driven engagement with the driving cam, and a locking pin thereon engageable in

the holes in the disc, a slideable stop plunger mounted in parallelism with the driven shaft and having a frusto-conical head adapted to engage in the holes in the disc to stop the latter, the arcuate distance between the locking pin in its instantaneous position and the stop plunger being less than that between the approximately registering holes in the disc, whereby a slight additional rotation is imparted to the disc before

10 it is stopped, and means including a shiftable member movable in parallelism with said driven shaft and the axes of said cams and a cam follower carried thereby in driven engagement with the stopping cam and operatively connected to 15 said crank arm and stopping plunger for selectively moving either the locking pin or the stopping plunger into the approximately registering holes in said disc.

9. A mechanism for converting continuous rotary motion into intermittent motion of constant amplitude and period comprising a driving cam and a stopping cam both rotatable with the same angular velocity, a driven shaft mounted in parallel relationship with said cams, a driving

20 disc on said driven shaft having a plurality of radially positioned and arcuately spaced holes therein and concave peripheral sections between adjacent arcuately spaced holes, a rotatable crank arm slidably mounted with respect to said

25 driven shaft and having a follower thereon in driven engagement with the driving cam and a locking pin thereon engageable in the holes in the disc, a stopping disc mounted concentrically with respect to one of said cams and in phase

30 displacement with the stopping cam and having a peripheral notch therein adapted to receive the sections of the driving disc intermediate the concave peripheral sections, and means including a shiftable member movable in parallelism with 35 said driven shaft and the axes of said cams and a cam follower carried thereby in driven engagement with the stopping cam and operatively connected to said crank arm for moving the locking pin into one of the holes in said driving disc

40 when the peripheral notch in said stopping disc receives the sections of the driving disc intermediate the concave peripheral sections of the latter and for receiving the locking pin from the hole in the driving disc when the uninterrupted 45 periphery of the stopping disc is in engagement with one of the concave peripheral sections of the driving disc.
